UNITED STATES PATENT OFFICE

GOLDWIN S. SPRAGUE, OF NEWTON, MASSACHUSETTS

SKI BINDING

Application filed October 6, 1930. Serial No. 486,561.

This invention relates to the ski binding by which the boot of the skier is secured to the ski. The requirements of a proper ski binding are severe because the well-known circumstances of use of skis are such that even the life of the skier may depend upon the ski binding, while at all times the comfort, pleasure and skill of the skier is dependent thereon.

Experienced skiers commonly provide themselves with special boots having heavy, substantially rigid soles which thus provide for proper cooperation with types of ski bindings especially designed therefor. But such boots are expensive and for ordinary purposes it is therefore desirable that a ski binding be provided which will enable the skier to make use of ordinary types of boots such as the well-known Barker boot or such as heavy arctics.

The principal object of this invention is therefore to provide a ski binding of durable, safe and practical construction which may be used in connection with Barker boots, arctics or other ordinary boots, particularly where the edge of the sole projects laterally beyond the upper and which allows the escape of snow and ice which would otherwise collect between the boot and the binding.

The object of the invention is further to provide such a ski binding which is adjustable to compensate for variations in boot sizes.

These and other objects of the invention will appear more fully from the accompanying description and drawings and will be particularly pointed out in the claims.

In the drawings:

Fig. 1 is a side elevation of a portion of a ski, a Barker boot, and a ski binding embodying a preferred form of the invention.

Fig. 2 is a view chiefly in vertical section taken on the line 2—2 of Fig. 1.

Fig. 3 is a top plan view of the construction shown in Fig. 1 without the boot and without the toe strap.

Fig. 4 is a view similar to Fig. 1 showing another form of the invention.

Fig. 5 is a top plan view without the boot of the construction shown in Fig. 4.

The ski may be of any usual type. Only a portion 1 thereof is illustrated. Such a ski is commonly provided with a slot 2 through which a toe strap may be passed.

As illustrative of an ordinary type of boot, there is shown a Barker boot. The vamp or lower portion 3 of this boot is usually of rubber having a heavy rubber sole 4, the edge of which projects to a substantial distance laterally beyond the upper. The portion 5 of the upper which extends up on the leg of the skier is usually of leather and is laced in position. The foot of the skier encased in the boot must be held by the binding exactly in proper position on the ski, while at the same time a hinging movement at the ball of the foot must be provided to allow the heel of the boot to swing toward and from the ski and without allowing the foot to twist laterally.

In the construction shown in Figs. 1 to 3, a longitudinally stiff sole plate 6 is secured at its forward end to the ski to permit the swinging movement of the plate on the ski. For these purposes the sole plate is itself transversely flexible and may be made of leather or a heavy treated textile material such as used for belting and be secured at its forward end as by the screws 7 directly to the ski so that the hinging movement is secured by the flexibility of the plate itself. The rigidity of the sole plate longitudinally, that is, in the direction of its length, gives the necessary longitudinal stiffness to the ski binding and insures the proper relation between the means provided for clamping the toe of the boot and the means provided for holding the boot at the rear.

A heel counter, which may be made of heavy leather or other suitable material, projects upward at 8 at each side of the rearward end of the sole plate and, in the construction illustrated, is rigidly secured to the sole plate by being bent thereunder and secured thereto by rivets 9. This binding counter presents a loop 10 extending rearward from the upwardly extending portions 8 of the counter. Thus this loop fits snugly against the counter of the boot and permits the boot sole heel 4 to project beneath the loop 10. Thus a very snug fit of the binding counter with the boot

is secured. The space or opening left beneath the loop of the binding counter and at the rear of the binding allows snow and ice, which would otherwise collect between the binding and the boot, to work out, which is a great practical advantage.

A suitable adjustable connection is provided between the upper front portions 11 of the binding counter to extend over the instep 10 of the boot and secure the boot in position. For this purpose a suitable strap is illustrated, one portion 12 of the strap having a buckle 13 being secured as by rivets to the binding counter at one side and the other portion 14 of the strap which cooperates with the buckle being similarly secured to the binding counter at the opposite side.

Suitable means are also provided for clamping and positioning the toe of the boot 20 to the ski at the forward end of the sole plate.

In the construction illustrated in Figs. 1 to 3, there is shown a pair of toe plates 15 of similar but reverse construction, each of which is angularly and laterally adjustably 25 secured to the ski. This angular and lateral adjustment is effected by screws 16 passing through slots 17 in the toe plates into the ski. These toe plates are each provided with an outer upstanding flange to engage the side 30 edge of the boot sole toe and hold it against lateral displacement. The pair of toe plates illustrated are similar to a type heretofore in use for gripping the edge of a heavy leather sole. In this invention such toe 35 plates may be utilized and for that purpose upstanding flange members 18 are secured as by screws 19 to the inner surfaces of the usual edge-engaging portions 20 formed on the toe plates. These flanged portions 18 are each 40 provided with an aperture 21 extending therethrough and adapted to receive a strap.

A strap 22 is preferably passed through these apertures with its middle portion extending over the toe of the boot and with its 45 ends brought together over the toe of the boot and buckled together. This construction provides a very firm adjustable means both for clamping the toe of the boot to the ski and preventing lateral movement of the boot 50 at the toe, while at the same time it provides for adjustment for all sizes of boot toes.

The construction shown in Figs. 4 and 5 is similar to that described except in the following particulars.

55 In this construction the longitudinally stiff but transversely flexible sole plate 23 extends beneath the toe of the boot and is secured at its extreme forward end by the screws 24 to the ski.

60 That portion of the ski binding engaging the heel and instep of the boot is of the same construction as described, except that in addition the rearward loop of the ski binding counter is made adjustable so as to compensate for variations in boot lengths. For this

purpose the rearward extending loop 25 of the binding counter is separated at the center and the loop is completed by a strap, one portion 26 of which is attached as by rivets to the binding counter at one side and the other portion 27 of which is attached as by rivets to the binding counter at the opposite side. Thus by adjusting the length of the strap, as by means of the buckle 28, the length of the rearward extending loop of the binding counter may be varied to cause the counter to fit a boot of any length.

This adjustable feature of the ski binding counter may, of course, be embodied in either 80 or any form of the invention.

The construction illustrated in Figs. 4 and 5 also serves to illustrate that various types of toe binding may be employed in connection with the counter binding of this invention. In this construction a simple ordinary 85 type of toe binding is shown comprising the strap 29 passed through the usual slot 2 in the ski and buckled over the toe of the boot.

Having thus described the invention, what 90 is claimed as new, and desired to be secured by Letters Patent, is:

1. A ski binding comprising a longitudinally stiff sole plate, means for securing the forward end of the sole plate to the ski to permit the swinging movement of the 95 plate on the ski, a heel counter projecting upward from the sole plate at each side of its rearward end and presenting a rearward loop allowing the counter to fit snugly around the counter of a boot with the boot sole heel 100 projecting beneath the loop, an adjustable connection between the upper front portions of the binding counter to extend over the boot instep, and means for clamping the toe of the boot to the ski at the forward end 105 of the sole plate.

2. A ski binding comprising the construction defined in claim 1, together with means for adjusting the length of the said rearward 110 loop of the binding counter to compensate for variations in boot lengths.

3. A ski binding comprising a longitudinally stiff sole plate, means for securing the forward end of the sole plate to the ski to permit the swinging movement of the plate on the ski, a heel counter projecting upward from the sole plate at each side of its rearward end and presenting a rearward loop allowing the counter to fit snugly around the counter of a boot with the boot sole heel 115 projecting beneath the loop, an adjustable connection between the upper front portions of the binding counter to extend over the boot instep; a pair of toe plates each having an outer upstanding flange to engage a side 120 edge of the boot sole toe, means for securing the toe plates to the ski, and an adjustable connection between the flanges to extend over the boot sole toe and clamping the boot 125 toe to the ski.

4. A ski binding comprising a longitudinally stiff sole plate, means for securing the forward end of the sole plate to the ski to permit the swinging movement of the plate
5 on the ski, a heel counter projecting upward from the sole plate at each side of its rearward end and presenting a rearward loop allowing the counter to fit snugly around the counter of a boot with the boot sole heel projecting beneath the loop, an adjustable connection between the upper front portions of the binding counter to extend over the boot instep, a pair of toe plates each having an outer upstanding flange to engage a side
10 edge of the boot sole toe, means for adjustably securing both angularly and laterally each toe plate to the ski, and an adjustable connection between the flanges to extend over the boot sole toe and clamping the boot toe
15 to the ski.

5. A ski binding comprising a longitudinally stiff sole plate, means for securing the forward end of the sole plate to the ski to permit the swinging movement of the plate
20 on the ski, a heel counter projecting upward from the sole plate at each side of its rearward end and presenting a rearward loop allowing the counter to fit snugly around the counter of a boot with the boot sole heel projecting beneath the loop, an adjustable connection between the upper front portions of the binding counter to extend over the boot instep, a pair of toe plates each having an outer upstanding flange to engage a side
25 edge of the boot sole toe, each flange having an aperture therethrough, and an adjustable strap passed through said apertures adapted to extend over the boot toe and thus to hold the boot toe in position on the ski between
30 the toe plates.

In testimony whereof, I have signed my name to this specification.

GOLDWIN S. SPRAGUE.
